UNITED STATES PATENT OFFICE.

JAMES SANGSTER AND AMOS W. SANGSTER, OF BUFFALO, NEW YORK,
ASSIGNORS TO THOMAS J. COURY, OF SAME PLACE.

IMPROVEMENT IN PARLOR STOVES.

Specification forming part of Letters Patent No. 44,222, dated September 13, 1864.

To all whom it may concern:

Be it known that we, JAMES SANGSTER and AMOS W. SANGSTER, of Buffalo, in the county of Erie and State of New York, have invented certain new and useful Improvements in Stoves; and we do hereby declare that the following is a full and exact description thereof, reference being had to the accompanying drawings, and to the letters of reference marked thereon.

The nature of our invention consists in providing the stove with a tube passing up from the bottom through the center to the top, with a movable grate, the center of which surrounds the tube, and a removable sifter, the center of which forms the lower part of the tube; also, in providing the upper part of the stove with an oven, which bakes or cooks by the heat which is generated within the tube which passes up through the fire in the center of the stove; also, in so constructing the top of the stove that the hot air, when not used for baking or cooking, is thrown downward and through the room.

To enable others skilled in the art to make and use our invention, we will proceed to describe its construction and operation.

We construct our stove of the usual materials, cast and sheet iron, or cast-iron alone.

The same letters in Figures 1, 2, 3, and 4, represent similar parts in each.

Fig. 1 represents a section view cut down vertically through the stove, showing the tube in the center, the oven, the grate, and the sifter. Fig. 2 is a side elevation of the stove complete; Fig. 3, the grate; and Fig. 4 is the sifter.

In Fig. 1, A is the cover. P is a light-reflecting surface made of tin-plate. This cover stands upon four legs or pillars, (each marked R,) between which the air has a free passage, as shown by the arrows. B is the cover which is used while baking. D is a platform upon which bread or other articles to be cooked or baked are placed. This platform also stands upon legs to allow a passage for the air. E is the outside casing of the stove. G is the coal-chamber. O is a perforated case surrounding the fire-box. (It is shown more plainly in Fig. 2.) H is the grate upon which the coal is placed. K is the bottom of the stove,

and L the legs. F is the tube, which passes through the center of the fire and stove. I is the sifter. It can be taken out at any time to sift the ashes and cinders that drop through the grate. J is a tube which is fastened to the center of the sieve. S is a flange which projects down from the bottom of the tube F. This flange is made something in the shape of a horseshoe. (More plainly seen in Fig. 5.) When the sifter is placed in the stove, the tube J slips under the tube F and completes the tube through the stove. In slipping under the tube F, the tube J passes into the flange S, as plainly shown in Fig. 5. It is thus easily disconnected.

In Fig. 2, U is the door. V is the damper. N, the handle to the grate, by which it is moved while shaking out the ashes. (It is more plainly seen in Fig. 3. This handle is covered up when the damper is in its place. M is the handle to the sieve, which is more clearly seen in Fig. 4. Its operation is simple. The fire surrounding the tube F creates a draft upward through the center of the stove and carries with it part of the heat (which is generally wasted) from the center of the fire and distributes it through the room or within an oven for cooking or other purposes. W and W' is an additional tube, which passes up the side of the stove and connects with the center tube near the top part of the stove. W represents that tube in Fig. 3. The stove can be used either with or without this tube W. X is a damper at the bottom of the tube J in the center of the sieve. This regulates the draft of air up through the stove. Y is a damper for the same purpose in the tube W. These dampers are made in the usual way.

What we claim as our invention, and desire to secure by Letters Patent, is—

1. The central tube, F, passing through the stove, with a flange at its bottom, as shown in Fig. 5, also the tube J, which forms the center of the sieve and continues the tube F down through the bottom of the stove by connecting with it at the bottom, as shown in Fig. 5, by means of the flange S, also the funnel shape of the upper part of the tube F, as shown at Z, also the tube W W', as shown and described.

2. The cover A, standing upon legs, as de-

scribed, and with the reflecting surface P, also the cover B, combined with the platform D and the tube F.

3. The grate with the tube F passing through it, and the sieve I with the damper X in the center, and the tube J, for the purposes set forth; also the damper Y at the bottom of the tube W.

4. The oven C, in combination with the tube F, when constructed and operated as herein substantially set forth and described.

JAMES SANGSTER.
AMOS W. SANGSTER.
